MERRY-GO-ROUND

Charles K. Webb, Shreveport, La.

Application June 10, 1946, Serial No. 675,718

4 Claims. (Cl. 272—43)

1

My invention relates to amusement devices, and particularly to carousels, popularly called merry-go-rounds.

An object of my invention is to provide a power driven merry-go-round that incorporates a power control located at one or more of the rider's seats of the merry-go-round, by means of which a rider may start and stop the merry-go-round.

Another object of my invention is to provide in carousel constructions an over-riding type of driving mechanism that makes use of a uni-directional high ratio worm drive mechanism permitting the use of a high speed small size motor as a source of power for operating the merry-go-round.

Another object of my invention is to provide a rugged type of merry-go-round construction supported in a manner to permit it to be used by a single rider.

Other objects and advantages of my invention will appear from the general description of my invention, and from a reading of the detailed description of a merry-go-round embodying my invention illustrated by my drawings.

My merry-go-round comprises a base member with a vertically extending shaft on which a horizontally rotatable carriage is rotatably mounted. The rotatable carriage as shown in my drawing provides four seats for riders. It is to be understood, however, that a greater or lesser number of riders' seats can be provided within the scope of my invention. The rotatable carriage is driven by means of an electric motor mounted on the base connected to a driving mechanism. The motor is designed to be controlled by one of the riders through the means of a motor control mechanism which is provided with a control handle conveniently located at the driver's seat. While the style of motor control illustrated in my drawings is of the mechanical type it is to be borne in mind that other types of motor control such as electric switches may be employed within the scope of my invention. That is to say, my invention envisions the broad concept of a power driven merry-go-round which includes any power control conveniently located at a rider's seat on the merry-go-round. The power lines lead out of an electric service, not shown, which is provided with a master control switch through the means of which the merry-go-round may be started and stopped independently of the control handle at the rider's seat.

Referring to the drawings, Figure 1 is a plan view of a power driven merry-go-round embodying my invention with a top part of its driving mechanism housing broken away to show details of construction;

Fig. 2 is an elevational view of the merry-go-round illustrated in Fig. 1, with a side part of

the driving mechanism housing broken away to show details of construction;

Fig. 3 is an enlarged elevational view, partially broken, of a part of the merry-go-round illustrated by Figure 1;

Fig. 3a is a detail plan view of one of the seats of the merry-go-round partially broken away to show the mechanism controlled therefrom;

Fig. 4 is an enlarged broken plan view of a part of the driving mechanism of the illustrated merry-go-round; and

Fig. 5 is an enlarged broken elevational view of the part of the driving mechanism illustrated by Fig. 4.

15 Referring to the drawings, numeral 10 designates the base member generally, which comprises four radially extending feet 11 joined to a base plate 12 bolted to the feet 11 by means of bolts 13. The base plate 12 is provided with an internally threaded, centrally positioned boss 14. A vertically extending tubular mast 15 is threadedly engaged with the boss 14. The tubular mast 15 is internally threaded at 16 at its upper end. The externally threaded bearing member 17 has a central vertically extending base 18. In assembling, the bearing member 17 is made up tight in the internally threaded portion 16 of the tubular shaft 15.

20 The bearing member 17 has its upper surface and its side wall surface smooth-faced to co-operate with bearing surfaces mentioned later on in this description. Bearing member 17 terminates in a vertically extending stud 20 on which a removable bearing collar 21 is mounted. The bearing collar 21 is prevented from moving upwardly by the stop collar 22 which is fastened to the stud 20 by the set screw 23. A washer 24 is placed between the stop collar 22 and the bearing collar 21 to reduce friction.

25 The rotatable member of the merry-go-round hereafter referred to as the rotatable carriage is designated generally by numeral 26. The weight of the entire rotatable carriage 26 is supported by the carriage bearing shell 27 which revolves on the bearing member 17.

30 The lower internal peripheral bearing surface 28 of the bearing shell 27 contacts the upper faced surface of the supporting bearing 17 to steady the carriage 26 when it tilts only slightly out of its normal horizontal plane position. The lower circular, vertical, bearing surface 29 of the bearing shell 27 prevents the bearing shell 27 from drifting off of the supporting bearing 17. The upper horizontal bearing surface 30 and the upper vertical bearing surface 31 contact the bottom and side surfaces, respectively, of the above mentioned bearing collar 21.

35 Through the means of these contacts the carriage 26 is prevented from tilting out of its horizontal plane of rotation any substantial amount

when the load carried by the carriage 26 is unbalanced, such as when a single child is riding the merry-go-round. The weight of the carriage 26 rests on the peripheral shoulder 32 of the carriage bearing shell 27. The carriage bearing shell 27 is provided with a plurality of peripherally spaced vertically extending threaded sockets 33 in which stud bolts 37 are screwed.

An internally shouldered sleeve 34 rests on the peripheral shoulder 32 of the carriage bearing shell 27. This sleeve 34 helps to hold the bearing shell 27 in its proper horizontal operating position. The shouldered sleeve 34 is preferably welded to a hub plate 35 over which lies a spider plate 36. The stud bolts 37 mounted in the sockets 33 extended through the hub plate 35 and spider plate 36, together with the nuts 38, are used to assemble the carriage bearing shell 27 with the sleeve 34, the hub plate 35, and the spider plate 36 into a rotatably mounted supporting frame structure on which other members of the carriage 26 may be mounted.

Four radially extending seat supporting arms 39 are bolted to the spider plate 36 through the means of bolts 40 and nuts 41. The driving mechanism housing 42 hung on the arms 39 comprises a vertical wall portion 43 and a removable cap 44. The housing 42 protects the motor M and other working parts of the merry-go-round from rains. The seat supporting arms 39 are extended through holes 45 in the sides of the vertical wall portion 43 of the housing 42. The removable cap 44 may be lifted off easily for purposes of inspection.

The seats 46 (see Figure 3 of the drawings) are rested on the outer ends of the seat supporting arms 39. The seat 46 is prevented from turning about the arm 39 by means of a pair of clamps 47 fastened to the under side of the seat 46 and clamped to a rod 48 extended in a horizontal direction through an end portion of a seat supporting arm 39. Each of the seats 46 is provided with a pair of handle bars 49 mounted on a vertically extending member 50 which simulates a horse's head.

A horizontally extending motor support 25 is welded to the side of the mast 15 at a position below the bearing member 17 to support the electric motor M, a motor control mechanism, and an overriding driving mechanism, designated generally by numeral 52, detailed description of which will follow.

The carriage 26 is rotated by means of the driven pulley shell 51. The pulley shell encloses some of the movable members described above.

The carriage 26 is rotated by means of the motor M, whose driving shaft S is connected to the overriding driving gear designated generally by numeral 52. The overriding driving gear 52 not only serves as a speed reducing gear but also functions as a slip clutch in that it will permit the carriage 26 to continue rotating after the motor M has been shut off.

The overriding driving gear 52 is provided with a housing 53 in which a worm gear 54 is rotatably mounted enmeshed with the ring gear 55, also rotatably mounted in the housing 53. The ring gear 55 is provided with a hub portion 56 through which is drilled oil holes 57 to supply part of the lubricant contained in the housing 53 to the bearing surfaces of the hub 56 and the bearing surface of the driving shaft 58 on which it is rotatably mounted.

The ring gear 55 carries a pawl stud 59 on which a driving pawl 60 is pivotally mounted. A

spring 61 is employed to releasably hold the pawl 60 in engagement with a ratchet wheel 62. The worm gear 54 and the ratchet wheel 62 rotate together during the period of time the motor M is running. When the motor M stops running the ratchet wheel 62 due to the momentum of the revolving carriage 26 runs away from the worm gear 54, and while doing so it moves the pawl 60 against the tension of the spring 61 out of its way into the dotted line position as best shown in Figure 5.

The hub 63 of the ratchet wheel 62 is provided with oil bores 65 adapted to supply a lubricant to the bearing surfaces of the hub 63 of the ratchet wheel 62 and the ring gear hub 56 on which it turns.

The ratchet wheel 62 is joined to driving shaft 58 by means of a pin 64 extended entirely through the hub 63 and the driving shaft 58. The driving shaft 58 is extended out of the housing 53 through a sleeve bearing 66 mounted in the housing 53. The driving pulley 67 is fastened to the driving shaft 58 by means of a key 68. A driving belt 69 is extended around the driving pulley 67 and the driven pulley shell 51 mentioned earlier in this specification.

While my drawing illustrates a mechanism employing a direct drive from motor M to the overriding driving gear 52 in which the driving speed is reduced properly to effect a slow rotation of the carriage 26, it is to be understood that the motor M may be arranged to drive the worm gear 54 through an arrangement of pulleys and a belt.

In describing the individual motor control I will commence with the motor control switch 70 as seen in Fig. 3 by means of which the current supplied to the motor M may be controlled when the master switch, not shown, is closed.

The motor control switch 70 is of the type that is sensitive enough to be operated by slight movements of its switch control arm 71, which is moved by means of the bell crank lever 72 in a manner to be explained hereafter.

The bell crank lever 72 is pivotally mounted in the lever bracket 73 fastened to the mast 15. The bell crank lever 72 is provided with a spring contacting lug 74 which is positioned to strike the tip end of the switch control arm 71. A compression spring 75 mounted on a rod 76 which is fastened to the mast 15 is extended through a hole in an arm of the bell crank lever 72.

The spring 75 is depended upon to hold the bell crank lever 72 in the out-of-contact solid line position shown in Figure 3 of the drawings. The tension of the spring 75 is adjusted by means of the adjusting nut 77 threadedly engaged on the outer end of the rod 76.

The spring 75 must be compressed to cause a movement of the bell crank lever 72 to make it contact and move the switch control arm 71 into the dotted line position, the "on" position of the switch 70, the position in which the electric current is conducted to the motor to set it in motion.

The spring 75 must be permitted to expand to effect a movement of the switch 70 to "off" position. The spring 75 is permitted to expand when the weight rod 78 and the plunger 79 it supports are free to move and be lifted by the bell crank lever 72. The weight rod 78 extends loosely through the bearing member 17 and the stop collar 22. Under normal inoperating conditions the spring 75 is in its expanded position and supports the weight of the weight rod 78 resting on one end of the bell crank lever 72.

positioned inside of the mast 15 and also supports the plunger 79.

When the weight rod 78 is pushed downwardly the bell crank lever 72 is moved about its pivot point in the lever bracket 73, overcoming the compression spring 75 to bring the switch control lug 74 (on the bell crank lever) into contact with the end of the switch arm 71 to affect the movement of the same sufficiently to operate the control switch 70 into its "on" position.

The weight rod 78 is moved downwardly by means of a plunger 79 resting on the upper end of the weight rod 78. To the upper end of the plunger 79 a cable 80 is joined which extends around a pulley 81 rotatably mounted on the spider plate 36 at a position below the upper end of the plunger 79 to which the cable 80 is attached. The cable 80 is extended also through a seat supporting arm 39. The outer end of the cable 80 is connected to a small bell crank lever 86 pivotally mounted in the lever bracket 82, preferably welded to the seat supporting arm 39.

A short cable 83 is connected to the other end of the lever 81 and is extended around a pulley 84 mounted on the under side of the seat 46. The short cable 83 is further extended through a hole in the seat 46 up to a spool 85 on which it is wrapped around and secured. The spool 85 is rotatably mounted on a handle bar 49.

A brief explanation now of the operation of this individual motor control mechanism will assist in the understanding of the control mechanism itself. When a child sitting on the seat 46 of the merry-go-round winds the short cable 83 tighter around the spool 85 the short cable 83 effects a movement of the small bell crank lever 86, which movement moves the cable 80 to the left to pull its inner end down and the plunger 79 down with it.

The downward movement of the plunger pushes the weighted rod 78 downwardly, overcoming the compression spring 75 in its movement of the bell crank lever 72 into the dotted line position. In the movement of the bell crank lever 72 into this dotted line position the switch operating lug 74 is brought into contact with the control arm 71 of the electric switch 70 to throw the switch 70 into the "on" position to start the motor M running and to rotate the carriage.

As soon as the child releases his grip on the spool 85 the compression spring 75 expands and moves the bell crank lever 72, back to the solid line position, allowing the switch 70 to throw itself back into the "off" position, it being remembered that the compression spring 75 was set to accomplish this movement of the bell crank lever 72 by means of the spring adjusting nut 77. When the current is shut off the carriage coasts to a stop.

Having thus described my invention I claim:

1. A merry-go-round comprising a base member, a hollow mast vertically extending from said base member, a carriage rotatably mounted on said hollow mast, said carriage provided with rider's seats, an electrical driving means connected in a manner to rotate said carriage, said driving means being provided with a speed reduction gear, a control switch, adapted to be thrown into an "on" position or an "off" position, a control switch operating mechanism comprising a lever pivotally mounted on said hollow mast at a medial portion of the length of said lever, said lever being mounted on said mast for movement in a vertical plane, said mast provided with an aperture in its side wall through which

one arm of said lever extends, said other arm of said lever being positioned to operate said control switch, a rod slidably mounted in said hollow mast, aligned to have its lower end rest on said first mentioned arm of said lever, and means controlled from the rider's seat for actuating said rod for movement with respect to the arm of said lever whereby a movement of said rod effects a movement of said lever which in turn operates said control switch.

2. The device as claimed in claim 1 provided with a compression spring adapted to normally hold said first mentioned arm of said lever in a substantially horizontal position in said hollow mast corresponding to said "off" position of said control switch while supporting the entire weight of said rod, said compression spring being sufficiently yieldable to allow a movement of said lever by said rod to effect a movement of said control switch into its "on" position.

3. A merry-go-round comprising a base member, a hollow mast vertically extending from said base member, a carriage rotatably mounted on said mast, said carriage provided with rider's seats, an electrical driving means including a speed reduction gear and an overriding clutch supported by said mast adapted to allow said carriage to rotate under its own momentum after said driving means is stopped, a control switch adapted to control said driving means, and a switch operating mechanism adapted to actuate said switch, said switch operating mechanism comprising a double-armed lever pivotally mounted at a medial portion of its length on said mast in a manner to permit it to move in a vertical plane, one arm of said lever positioned and adapted to operate said switch while its other arm is maintained in contact with a vertical slideable rod slidably mounted in said hollow mast, said rod adapted to move said lever to effect a movement of said operating switch, a rod moving means comprising a cable extended through a pulley located below said upper end of said rod, the end of said cable attached to said upper end of said rod, and a means for moving said cable located at said rider's seat attached to the other end of said cable effected by said means for moving said cable, whereby a pull on said cable will effect a downward movement of said rod which in turn will effect, by means of said lever, a movement of said switch.

4. The device as claimed in claim 3 wherein said means for moving said cable includes a spool rotatably mounted on said seat and a second cable having one of its ends attached to the outer surface of said spool and its other end connected with the outer end of said first mentioned cable by a pivotally mounted double-armed lever, one arm of which is attached to said first mentioned cable and the second arm of which is attached to said second mentioned cable.

CHARLES K. WEBB.
